[57] CLAIM

The ornamental design for a clamp for clamping wires, as shown and described.

DESCRIPTION

FIG. 1 is a top view of a clamp for clamping wires showing my new design;
FIG. 2 is a left side view thereof;
FIG. 3 is a front view thereof;
FIG. 4 is a right side view thereof;
FIG. 5 is a bottom view thereof;
FIG. 6 is a rear view thereof;
FIG. 7 is a sectional view taken in the direction of the arrows on line 7—7 of FIG. 3;
FIG. 8 is a sectional view taken in the direction of the arrows on line 8—8 of FIG. 3;
FIG. 9 is a front view thereof, the broken line showing of the panel being for illustrative purposes only;
FIG. 10 is a top, front perspective view thereof;
FIG. 11 is a bottom, front perspective view thereof.
